UNITED STATES PATENT OFFICE.

EDWARD WOLF, OF BALTIMORE, MARYLAND.

LETTER-BOX.

SPECIFICATION forming part of Letters Patent No. 507,956, dated October 31, 1893.

Application filed December 22, 1892. Serial No. 456,053. (No model.)

To all whom it may concern:

Be it known that I, EDWARD WOLF, a citizen of the United States, and a resident of Baltimore city, in the State of Maryland, have 5 invented a certain new and useful Improvement in Letter-Boxes, of which the following is a description.

This invention relates to an improvement in letter boxes, and more particularly to that 10 class employed in street service.

The object of the invention is to produce a letter box of the above description which will effectually prevent unauthorized removal of the mail matter when once deposited.

15 A further object is to provide a letter box having its walls so constructed as to prevent any catching of mail matter between the said walls and the pocket when the latter is turned down for the removal of the mail matter.

20 A further object is to provide a mail box having a removable bottom whereby to facilitate the depositing of the mail matter within a bag, thus obviating the necessity of thrusting the hand within the box for that purpose, 25 as with mail boxes of the ordinary construction.

With these objects in view the invention consists in the novel construction and combination of parts of a mail box as will be hereinafter fully described and claimed.

30 In the accompanying drawings forming a part of this specification, and in which like numerals of reference indicate corresponding parts, Figure 1, is a vertical transverse section of the mail box constructed in accordance with my invention. Fig. 2, is a vertical longitudinal sectional view of the same. Fig. 3, is a perspective view of the shutter and its attached mechanism removed from the box.

40 Referring to the drawings, 1, designates the box, the upper portion of which is provided with a curved top 2, a ledge 3, and a pivoted flap or shutter 4 for closing the mail opening. The flap or shutter is pivoted at its lower end 45 in the respective sides of the box by means of a pintle or rod 6, and is provided at its upper end and at each side with a lug or projection 7, and a continuous flange 8, extending at an angle to the shutter proper and 50 forming a stop. At a point near the rear side of the box, and on each side thereof, is pivoted a link 9 to which is secured a deflecting

plate 10, either integrally or by means of suitable fastening devices. To each of the links 9 is pivotally attached a lever-arm 11, the free 55 end of each of which is pivotally attached to one of the lugs 7 of the shutter. When the shutter is closed the deflecting plate assumes an angle sufficient to project the mail matter into the pocket, and when the shutter is 60 opened the deflecting plate is brought to the position indicated in dotted lines in Fig. 1, with the flange 8, bearing upon the plate and serving to limit its upward movement. The downward movement of the plate is limited 65 by means of a rigid stop 12, clearly shown in Fig. 1.

The pocket 13, to which reference has been made, is of the ordinary shape. As before stated, it is desirous to prevent any catching 70 of mail-matter between the sides of the pocket and the box, and in order to accomplish this result the lower portion of the side walls of the box are made double, as shown at 14, and between these double walls the sides of the 75 pocket work. The upper ends of the double walls are connected with the sides proper by means of an inclined piece 15, which serves to prevent any lodgment of mail at this point. The pocket is held in place by means of an 80 ordinary lock 16, such as is usually employed. The function of the pocket is to permit of the removal of the mail by the letter carrier in the usual manner, but should it be desirous to deposit the mail directly in a bag, such 85 construction would not be found to answer the purpose. In order to provide for this contingency the bottom 17, of the box is made removable and works in guides 18 formed in the lower portion of the sides of the box. 90 The upper surface of the bottom is provided with a series of ribs or corrugations 19 which are designed to be engaged by fingers 20 carried by an inclined partition or backing 21 secured to the rear wall of the box. To remove the bottom a lock 22 is unfastened, and the bottom drawn out. The fingers 20, will 95 effectually prevent the retention of any mail matter, which might occur if the bottom were left perfectly smooth.

100 From the foregoing description it will readily be seen that it will be impossible to rob a mail box from the mail opening, inasmuch as the shutter will have to be opened in or-

der to permit of the introduction of a wire or the like, and by the time the shutter has been moved down a sufficient distance to permit of the removal of any mail matter, the deflecting plate will have assumed a position which will further preclude the admission of the wire, while a further raising of the plate will bring the flange 8 into contact with it, and thus close ingress to the box.

10 Having thus fully described my invention, what I claim as new, and desire to secure by Letters Patent, is—

15 1. A mail-box having a mail-opening and a shutter pivoted at its lower end and arranged to close the said opening and having a rearward extending flange on its upper portion, in combination with a pivoted deflecting-plate

located in rear of the shutter and having its pivoted portion approximately in alignment therewith, and lever-arms connecting the shutter and the said plate, whereby when the former is swung inward the plate will be raised and brought into contact with the said flange.

2. A mail-box having a removable bottom provided with a corrugated or ribbed upper surface, and fingers within the box co-acting with the ribs or corrugations.

In testimony whereof I hereunto affix my signature in the presence of two witnesses.

EDWARD WOLF.
